UNITED STATES PATENT OFFICE.

PHILIP D'H. DRESSLER, OF ZANESVILLE, OHIO, ASSIGNOR TO AMERICAN DRESSLER
TUNNEL KILNS, INC., OF NEW YORK, N. Y., A CORPORATION OF NEW YORK.

TUNNEL-KILN.

1,330,433.

Specification of Letters Patent. Patented Feb. 10, 1920.

Application filed May 28, 1919. Serial No. 300,445.

To all whom it may concern:

Be it known that I, PHILIP D'H. DRESSLER, a subject of the King of Great Britain, and resident of Zanesville, in the county of 5 Muskingum and State of Ohio, have invented certain new and useful Improvements in Tunnel-Kilns, of which the following is a specification.

My present invention relates to tunnel 10 kilns in which a high temperature zone is maintained in the kilns at a distance from the head or entrance end of the kiln and in which the portion of the kiln between the high temperature zone and the entrance end 15 forms a heating up zone through which the temperature varies more or less gradually from one end to the other. In such a kiln as the goods mounted on cars are moved slowly through the kiln from its entrance 20 end to and through the high temperature zone, the goods are gradually brought up to the high temperature prevailing in the high temperature zone.

The object of the present invention is to 25 provide simple and effective means whereby the temperature graduation in the heating up zone of the kiln is controlled, and my invention preferably comprises means whereby the temperature in the heating up zone 30 of the kiln may be adjusted to meet different operating conditions.

My present invention was primarily devised as improvement on the well known 35 Dressler tunnel kiln in which the high temperature zone of the kiln is heated by the combustion of gas in the combustion chambers located within the kiln at the high temperature zone thereof, and in which the products of combustion are withdrawn from 40 the combustion chambers proper through conduit extensions thereof passing through the heating up zone of the kiln to a point adjacent the head end of the kiln where these conduits are connected to some draft 45 creating device such as an exhaust fan or stack. In this type of kiln the heat remaining in the products of combustion leaving the combustion chamber proper is to a large extent radiated from the walls of the con- 50duit connecting the combustion chambers to the draft creating device, and the heat thus radiated is absorbed by the goods passing through the heating up zone of the kiln. In this type of kiln there is, in general, 55 more heat remaining in the products of

combustion leaving the high temperature zone of the kiln than is required to heat the goods up to the temperature at which they should enter the high temperature zone. To avoid a too rapid heating of the goods, 60 very undesirable with certain classes of goods, it has been the practice to make the heating up zone longer than would be otherwise necessary to retard the rapid heating up of the goods, and a specific object of the 65 present invention is to provide simple and effective means whereby the slow and gradual heating up of the goods may be obtained with a heating up zone of shorter length than has heretofore been employed. 70 To accomplish this I provide means whereby the temperature of the gaseous products in the conduits passing through the heating up zone may be reduced.

The various features of novelty which 75 characterize my invention are pointed out with particularity in the claims annexed to and forming a part of this specification. For a better understanding of the invention, however, and the advantages possessed by it 80 reference should be had to the accompanying drawings and descriptive matter in which I have illustrated and described a preferred embodiment of my invention.

Of the drawings:

Figure 1 is a plan in section on the line 1-1 of Fig. 2 of a portion of a tunnel kiln provided with my present invention.

Fig. 2 is an elevation in section on the line 2-2 of Fig. 1.

In the drawings I have illustrated the application of my invention to a tunnel kiln of the well known Dressler type. In the kiln shown, A represents the kiln chamber proper, and B the ante chamber at the entrance or head end of the kiln. Track rails C are provided at the bottom of the chamber for the goods carrying cars L, and benches D are provided at the sides of the track on which are mounted the combustion chambers E. 95 Each combustion chamber E is connected, at the junction between the heating up and high temperature zones of the kiln, to a header F at the corresponding side of the kiln. Each header F which is ordinarily 100 made of cast iron is connected by one or more conduits G usually in the form of iron pipe to a junction box or header H adjacent the head end of the kiln. The two boxes H are connected by a conduit I to the 105

85

90

110

draft creating device, shown in the drawings as a stack J. Dampers K K are employed to regulate the draft actually imposed on each header H and thereby on the corresponding conduits G and combustion chamber E. The goods carrying cars L comprise car bodies fitting closely between the benches D and thereby protected in a large measure from the high temperatures prevailing in the 10 upper portion of the kiln chamber. The goods N mounted on the cars pass up between the two combustion chambers E and sets of conduits G to a level adjacent that of the top of the kiln chamber. It will be 15 understood that in operation, fuel, usually gas, is burned in the combustion chambers which are of suitably refractory material, and the gaseous products of combustion are carried out of the combustion chambers 20 through the conduits G by the stack suction. In so far as above described the apparatus shown contains nothing now novel with me.

The means which I have shown in the 25 drawings for lowering the heat radiating capacity of the conduit G in accordance with the present invention comprises means for admixing with the waste products of combustion leaving the combustion chambers, a cooling agent such as atmospheric air. For this purpose I provide tubular inlets M leading through the side walls of the kiln chamber into the junction boxes or headers F. As shown these tubular inlets 30 are the form of iron pipes located in ports A¹ formed in the masonry structure of the kiln and each having an internal diameter substantially greater than the external diameter of the corresponding pipe M so that 35 there is a capacity for adjustment of the inlets M lengthwise of the tunnel as the combustion chambers E and conduits G elongate and shorten as with temperature variations. The space between the inner 40 walls of the ports M and the outer walls of the inlet pipes M may be luted with clay or the like to prevent the leakage of air into the kiln chamber proper. Advantageously the inlet pipes M are provided with 45 dampers or throttling devices M¹ whereby the amount of air drawn into the junction boxes or headers F through the pipes M 50 may be varied to meet different operating conditions.

55 With the arrangement described the maximum temperature of the conduits G and thereby the effective heat radiating capacity of these conduits is reduced by the admission of atmospheric air to the headers 60 F through the inlet pipes M. In consequence it is possible to obtain a sufficiently gradual heating up of the goods passing through the heating up zone with a shorter length of heating up zone than has heretofore been required.

While in accordance with the provisions of the statutes I have illustrated and described the best embodiments of my invention now known to me, it will be apparent to those skilled in the art that changes may be made in the form of apparatus disclosed without departing from the spirit of my invention as set forth and that under some conditions certain features of my invention may be used to advantage without the corresponding use of other features.

Having now described my invention, what I claim as new and desire to secure by Letters Patent, is:

1. In a tunnel kiln comprising a high temperature zone and a heating up zone between the high temperature zone and the goods entrance end of the kiln and having a combustion chamber space in the high temperature zone and an extension of said space 85 passing through said heating up zone, said chamber and extension space being separated from the kiln chamber proper by heat conducting walls, the improvement which consists in provisions for supplying a cooling fluid to said combustion chamber extension space.

2. In a tunnel kiln comprising a high temperature zone and a heating up zone between the high temperature zone and the goods entrance end of the kiln and having a combustion chamber space in the high temperature zone and an extension of said space 95 passing through said heating up zone, said chamber and extension space being separated from the kiln chamber proper by heat conducting walls, the improvement which consists in an air inlet to said extension space.

3. In a tunnel kiln comprising a high 105 temperature zone and a heating up zone between the high temperature zone and the goods entrance end of the kiln and having a combustion chamber space in the high temperature zone and an extension of said 110 space passing through said heating up zone, said chamber and extension space being separated from the kiln chamber proper by heat conducting walls, the improvement which consists in a regulable air inlet to 115 said extension space.

4. In a tunnel kiln comprising a high temperature zone and a heating up zone between the high temperature zone and the goods entrance end of the kiln and having 120 a combustion chamber in the high temperature zone and a conduit extension thereof passing through said heating up zone, the improvement which consists in an air inlet to said conduit adjacent its connection to the 125 combustion chamber.

Signed at city of Zanesville, in the county of Muskingum and State of Ohio this 19th day of May A. D. 1919.

PHILIP D'H. DRESSLER.
